UNITED STATES PATENT OFFICE

2,158,862

SOCKET

Roscoe G. Phelps, Cleveland, Ohio, assignor to
General Electric Company, a corporation of
New York

Application February 12, 1937, Serial No. 125,409

17 Claims. (Cl. 173—346)

The present invention relates to electric sockets of the type having provisions for preventing short-circuit of the terminals thereof when the socket is empty. Sockets of this type are particularly adapted for use in locations where there is some chance that pieces of tin foil or other metallic particles may fall into empty sockets and short-circuit the exposed terminals. For example, the socket is well adapted for use with strings of decorative lights, such as Christmas tree lights.

The object of my invention is to provide an improved construction and arrangement in sockets of this type and for a consideration of what I believe to be novel and my invention attention is directed to the accompanying description and the claims appended hereto.

In the accompanying drawing, Fig. 1 is a sectional elevation of a socket embodying my invention; Fig. 2 is a view similar to Fig. 1 with a lamp in the socket; Fig. 3 is an exploded perspective view of the diaphragm closing the lower end of the screw shell and the contact associated therewith, and Fig. 4 is a sectional elevation of a modification.

Referring to the drawing, the socket has a base or husk 1 of suitable molded insulating material. The base has a cylindrical recess 2 at its upper end in which the parts of the socket are assembled. At the lower end of the recess is a disk 3 of insulating material which rests on a shoulder 4. At the center of the disk is a rivet 5 which secures a terminal 6 to the underside of the disk. The head 7 of the rivet is on the upper side of the disk and serves as a contact for connecting the terminal 6 with the center terminal of the socket in a manner which is described below. Near the periphery of the disk is a rivet 8 which secures a terminal 9 to the underside of the disk. The head 10 of the rivet is on the upper side of the disk and serves as a contact for connecting the terminal 9 to the screw shell in a manner which is described below. In the use of the socket the terminals 6 and 9 are respectively connected to one of the line conductors. The line conductors extend from the terminals through an opening 11 in the lower end of the base. The space surrounding the terminals and conductors may be filled with a suitable insulating cement for holding the conductors in place. The manner of connecting the conductors to the terminals is not shown, it being well understood in the art.

On the upper side of the disk 3 is a spacing sleeve 12 of insulating material. On the upper edge of the sleeve 12 rests an assembly which

comprises a resilient metal stamping 13 and a resilient diaphragm 14 of insulating material. The metal stamping 13 is provided with a tongue 15 which fits in a notch 16 in the diaphragm and is bent against the upper surface of the diaphragm 5 to secure the parts together. The notch 16 serves to hold the parts in fixed angular relation. At the center of the diaphragm is riveted a contact 17 the upper end of which serves as a center terminal of the socket and the lower end of which is 10 directly above and spaced from the contact 7. When the socket is empty the contact 17 is therefore insulated from the line conductors. On the upper side of the diaphragm 14 is a screw shell 19 which is secured in the recess 2 by frictional 15 engagement of a flange 20 with the side walls 21 of the base. At the lower end of the screw shell is an inwardly projecting flange 22 having a depression therein (not shown) into which the tongue 15 fits. The tongue 15 makes contact with a portion 23 of the flange 22. The metal stamping 13 is cut away to provide a flexible tongue 24 having a downwardly extending portion 25 at its free end which is directly above and is normally spaced from the contact 10. The intermediate portion of the tongue 24 is annular in shape, the lower end of the contact 17 extending through and being spaced from the edges of the opening 26 therein.

When a plug is threaded into the socket, as shown in Fig. 2, the center contact 18 of the plug engages the center terminal 17 of the socket and forces it downward into engagement with the contact 7, thereby completing a circuit from the line terminal 6 to the center terminal 17. The downward movement of the terminal 17 is made possible by flexing of the diaphragm. At the same time the tongue 24 which rests against the lower side of the diaphragm is forced downward until the downwardly extending portion 25 is forced into engagement with the contact 10 thereby completing a circuit from the line terminal 9 to the screw shell. When the plug is unthreaded from the shell, the diaphragm and the tongue 24 return to the position shown in Fig. 1 thereby breaking the circuit from the line terminals 6 and 9 to the screw shell 19 and the center terminal 17 of the socket. When the socket is empty the exposed terminals of the socket are therefore insulated and there is no danger of shortcircuiting the terminals by pieces of tin foil or other metallic particles which may fall into the empty socket.

In order to facilitate assembly of the socket, the disk 3, the spacing sleeve 12, the assembly comprising the metal stamping 13 and the dia- 55

phragm 14, and the lower end of the screw shell 19 are assembled in a sleeve 27 of insulating material. The assembled parts are then inserted into the upper end of the base and are held therein by the frictional engagement between the walls 21 and the flange 20 at the upper end of the screw shell. This construction has obvious advantages from the manufacturing view point.

Fig. 4 shows a modification of the socket in which the function of the sleeve 27 is filled by a sleeve 28 which is integral with the lower end of the screw shell. The other parts of the socket are of the same construction as the socket shown in Figs. 1 to 3, inclusive, the corresponding parts being denoted by the same reference characters. In the assembly of this socket the diaphragm 14 with the stamping 13 fixed thereto is inserted through the lower end of the sleeve 28. The tongue 15 makes contact with a flange 29 at the upper end of the sleeve 28. The spacing sleeve and the disk 3 are then inserted, the position of the disk 3 being such that the contact 10 is in alignment with the contact 25. The parts are then held in assembled relation by spinning over a flange 30 at the lower end of the sleeve 28. The screw shell with its assembled parts may then be pressed into the base and held therein by frictional engagement between the side walls 21 of the base and the flange 20 at the upper end of the screw shell.

The operation of the socket shown in Fig. 4 is identical with the operation of the socket shown in Figs. 1 to 3 inclusive.

What I claim as new and desire to secure by Letters Patent of the United States, is:

1. In an electric socket, a screw shell, a resilient diaphragm closing the lower end of the screw shell, said diaphragm being fixed at its edges, a center contact carried by said diaphragm and adapted to be engaged by the center contact of a plug threaded in the shell whereby part of the diaphragm is moved downward, a contact connected to said shell and arranged to be moved downward by said movement of the diaphragm, and contacts adapted to be connected to line conductors and arranged to be engaged by said center and shell contacts when in their downward positions, said center and shell contacts being separated from said line contacts when in their normal positions.

2. In an electric socket, a screw shell, a disk of insulating material closing the lower end of the shell, said disk being fixed at its edges and having an intermediate resilient part arranged to be flexed downward by a plug threaded in the shell, a contact adapted to be connected to a line conductor, and means for completing a circuit from said contact to said shell upon downward movement of said part, said circuit being normally open whereby said shell is insulated when empty.

3. In an electric socket, a screw shell, a disk of insulating material closing the lower end of the shell, said disk being fixed at its edges and having an intermediate resilient part arranged to be flexed downward by a plug threaded in the shell, a contact connected to said shell and arranged to be moved downward by the downward movement of said resilient part, a contact adapted to be connected to a line conductor and arranged to be engaged by said shell contact upon downward movement thereof, said shell and line contacts being normally separated.

4. In an electric socket, a screw shell, a resilient diaphragm closing the lower end of the shell

and arranged to have a part thereof flexed downward by a plug threaded in the shell, said diaphragm being fixed at its edges, a contact connected to said shell and arranged to be moved downward by said diaphragm, and a contact adapted to be connected to a line conductor and arranged to be engaged by said shell contact when in its downward position.

5. In an electric socket, a base, a unitary assembly adapted to be inserted in the base comprising a screw shell having a sleeve at its lower end in which are carried a center contact comprising the other terminal of the socket, a line contact for connection with a line conductor, and switching means adapted to close a circuit between said line contact and one of said socket terminals when a plug is threaded therein, said switching means maintaining said circuit open when the socket is empty.

6. In an electric socket, a base, a unitary assembly adapted to be inserted in said base comprising a screw shell having a sleeve integral with its lower end in which are carried a center contact comprising the other terminal of the socket, a contact adapted to be connected to a line conductor, and switching means adapted to complete a circuit between said line contact and one of the socket terminals when a plug is threaded in the socket, said switching means maintaining said circuit open when the shell is empty.

7. In an electric socket, a base, a unitary assembly adapted to be inserted in said base comprising a screw shell having a sleeve integral with its lower end, a member of insulating material in said sleeve closing the lower end of the shell, a disk fixed in said sleeve and carrying a contact adapted to be connected to a line conductor, and means including a contact extending through said member for effecting contact between said line contact and the center contact of a plug threaded in the socket, said contacts being separated when the socket is empty.

8. In an electric socket, a base, a unitary assembly adapted to be inserted in said base comprising a screw shell having a sleeve at its lower end in which are carried a center contact comprising the other terminal of the socket, said center contact being engaged by a plug threaded in the shell, a member of insulating material closing the lower end of said shell, said member having a flexible part adapted to be moved downward by a plug threaded in the shell, a contact below said member adapted to be connected to a line conductor, and means for completing a circuit from said line contact to one of the socket terminals upon downward movement of said part, said circuit being normally open whereby said socket is insulated when empty.

9. In an electric socket, a base having a recess, socket terminals comprising a screw shell fixed to the side walls of the recess and a center terminal carried therein, a member clamped between the base and the lower end of the screw shell carrying contacts adapted to be connected to line conductors, and a contact clamped between said member and the screw shell, said contact being normally separated from the line contacts and being movable downward into engagement with one of the line contacts by a plug threaded in the shell.

10. In an electric socket, socket terminals comprising a screw shell and a center terminal, a member at the lower end of the screw shell carry-

- ing contacts adapted to be connected to line conductors, a disk of insulating material closing the lower end of the shell, said disk being fixed at its edges and having a part intermediate its edges flexed downward by a plug threaded in the shell, and a resilient contact strip on the under side of the disk movable to a position completing a circuit between one of the socket terminals and one of the line contacts by downward movement of said intermediate part of the disk, said strip normally occupying a position in which said circuit is open.
11. In an electric socket, a screw shell, a disk of insulating material closing the lower end of the shell, said disk being fixed at its edges and having an intermediate part flexed downward by a plug threaded in the shell, a center terminal carried by said part, a resilient contact strip on the under side of said part connected to the screw shell and movable downward by downward movement of said part, and line contacts arranged to be engaged respectively by said center terminal and said contact strip upon downward movement of said intermediate part of said disk, said line contacts being separated from the center terminal and contact strip when the socket is empty.
12. In an electric socket, a screw shell, a disk of insulating material closing the lower end of the shell, said disk being fixed at its edges and having an intermediate part flexed downward by a plug threaded in the shell, a pair of line contacts, a resilient contact strip on the underside of the disk connected to the shell and movable downward by said disk into engagement with one of said line contacts, said strip having an opening therein and being normally separated from said line contact, and means for effecting connection between the other of said line contacts and the center contact of a plug threaded in the shell through the opening in said strip.
13. In an electric socket, a base, a unitary assembly adapted to be inserted therein comprising a screw shell having a sleeve at its lower end and a center terminal comprising the other terminal of the socket, a member of insulating material carried in the lower end of the sleeve, line contacts carried by said member, a disk of insulating material closing the lower end of the shell clamped between said member and the shell, said disk having a part movable downward by a plug threaded in the shell, and means operable by downward movement of said part for completing a circuit between one of the line contacts and one of the socket terminals, said circuit being open when the socket is empty.
14. In an electric socket, a base, a unitary assembly adapted to be inserted therein comprising a screw shell having a sleeve at its lower end and a center terminal comprising the other terminal of the socket, a member of insulating material carried in the lower end of the sleeve, line contacts carried by said member, means spacing axially the socket terminal and line contacts, and switching means above said member for effecting a circuit between one of the line contacts and one of the socket terminals by threading a plug in the shell, said circuit being open when the socket is empty.
15. In an electric socket, a base, a unitary assembly adapted to be inserted therein comprising a screw shell having a sleeve integral with its lower end and a center terminal comprising the other terminal of the socket, a member of insulating material carried at the lower end of the sleeve, line contacts carried by said member, a disk of insulating material above said member closing the lower end of the shell, and means between said disk and said member for effecting a circuit between one of the line contacts and one of the socket terminals upon threading a plug in the shell, said circuit being open when the socket is empty.
16. In an electric socket, a base, a unitary assembly adapted to be inserted therein comprising a screw shell having a sleeve integral with its lower end and a center terminal comprising the other terminal of the socket, a member of insulating material carried at the lower end of the sleeve, line contacts carried on said member, a disk of insulating material clamped between said member and the shell, said disk having a part movable downward by a plug threaded in the shell, and means operable by downward movement of said part for effecting a circuit between one of the socket terminals and one of the line contacts, said circuit being open when the socket is empty.
17. In an electric socket, a shell adapted to receive a plug, a closed chamber including a flexible wall having a plug contact and a shell contact, an opposed wall having contacts connected to line conductors, said flexible wall being adapted to be flexed by the insertion of said plug to effect closure of said plug contact and one line contact and said shell contact and other line contact to thereby connect said plug in circuit with said line conductors.

ROSCOE G. PHELPS.
